(57) **CLAIM**

The ornamental design for a combination glass cooktop and plastic peripheral frame for a cooking appliance, as shown and described.

DESCRIPTION

FIG. 1 is a top right perspective view of our new combination glass cooktop and plastic peripheral frame design for a cooking appliance;

FIG. 2 is an upper right perspective view of the combination glass cooktop and plastic peripheral frame of FIG. 1; FIG. 3 is a front elevational view of the combination glass cooktop and plastic peripheral frame of FIGS. 1 and 2, with the rear elevational view being identical;

FIG. 4 is a top plan view of the combination glass cooktop and plastic peripheral frame of the invention; and, FIG. 5 is a right side elevational view of the combination glass cooktop and plastic peripheral frame of the invention, with the left side elevational view being a mirror image thereof.

The broken lines showing the overall cabinet, control knobs, front control panel, heating element zones, and front door/handle assembly are for illustrative purposes only and form no part of the claimed invention.
